WASHER AND DRIER

Warren C. Paulson and Albert Kelley, Interna-
tional Falls, Minn.

Application August 10, 1939, Serial No. 289,468

1 Claim. (Cl. 141—9)

This invention appertains to new and useful improvements in washing and drying apparatus and more particularly to an apparatus for washing dishes and like utensils.

The principal object of the present invention is to provide an electric washer which in construction is adapted to thoroughly wash dishes and like articles in a minimum period of time with a minimum of fluid, and to dry articles quickly after fluid is drained therefrom.

Another important object of the invention is to provide a washer of the character described which requires only the manipulation of control members on a control board to cause starting, stopping, heating and draining operations in the machine.

Other objects and advantages of the invention will become apparent to the reader of the following specification.

In the drawings:

Figure 1 represents a side elevational view of the apparatus broken away to disclose the tub structure therein.

Figure 2 is a vertical sectional view through the apparatus.

Figure 3 is a horizontal sectional view taken substantially on the line 3—3 of Figure 2.

Figure 4 is a side elevational view of the impeller.

Figure 5 is an end elevational view of the impeller.

Figure 6 is a top plan view of the impeller.

Figure 7 is a vertical sectional view through the implement containing basket.

Referring to the drawings wherein like numerals designate like parts, it can be seen in the drawings and especially in Figure 2, that the apparatus consists of the shell 5 having the in-turned flange or ledge portion 6 at its lower edge and from the corner portions of which depend the legs 7.

Upon the ledge 6 rest the cleats 8 which are bridged by the platform 9 and on this platform 9 is mounted the electric motor 10 which has the lateral ears 11 disposed over slots 12 in the said platform with bolts 13 disposed downwardly through the ears 11 and slots 12 and capable of being loosened and tightened to permit adjusting and fixing of the motor 10 at a definite position on the said platform 9.

Risers 14 extend upwardly from the platform 9 to support the tub generally referred to by numeral 15. This tub 15 consists in construction of the sheet metal receptacle 16 which includes the side wall *a* and the bottom wall *b* and the

surrounding wall 17 of some suitable heat insulating material held in place by bands 18.

The upper edge portion of the receptacle 16 is disposed outwardly as at 19 and then upwardly and clinched over the upper edge of the shell 5 as at 20. Thus a shoulder 19 is defined at 19 upon which the packing strip 21 of the hinged lid 22 can rest. This lid 22 has a suitable latch or catch 23 and is hingedly secured in place as at 24.

In the receptacle 15 is the basket assembly generally referred to by numeral 25 and this consists of the substantially square frame 26 and the substantially centrally located annulus or ring 27. Ribs 28 extend from the ring 27 along the bottom *b* in a radial manner and for a substantial distance up the side wall *a* to connect to or merge with the frame 26. These ribs 28 form a bottom or base for the dishes or other articles which are to be placed in the basket 25.

Certain of the ribs 28 and the frame 26 are connected by guard members 29. These guard members extend obliquely from the frame 26 as shown in Figure 3. Dishes, saucers etc. are held by these rails 29 and also by the short guards 30 which are arranged in pairs and are of inverted U-shape, bridging certain of the ribs 28 and these guard rails 30 are located inwardly of the guard rails 29, that is, between the guard rails 29 and the annulus 27.

The annulus or ring 27 circumscribes the upwardly tapering mesh wall 31 which is topped by the plate 32. As can be seen in Figure 2, the central portion of the bottom *b* is provided with a pocket-like structure 33 in which is located the shell 34 in which is suitable filler material in which is embedded a heating element. Numeral 35 represents an electric cord extending to the heating unit.

The heating unit 34 has an open core through which the drive shaft 37 of the motor 10 extends, the shaft 37 also being disposed through a packing gland 37a. The heating unit has a depending formation 34b adapted to rest on the bottom of the pocket-like structure, the same having a plug-like formation 36 adapted to snugly extend through an opening in the bottom of the pocket-like structure. A nut 34c is provided on the plug-like formation. The upper end of this shaft 37 is constructed to take the impeller which is generally referred to by numeral 38. (See Figures 4 and 5.) The shaft 37 extends through a sleeve 37b which is disposed through the heating unit and interposed between the bottom of the pocket-like structure 33 and the impeller 38. This

impeller 38 operates within the confines of the wall 31 and is constructed in such a manner as to pick up the water from immediately above the heating unit 34 and to throw the same laterally in an upward direction with great velocity.

Numerals 39 represents the water drain pipe which has a valve 40 therein and this pipe connects to a laterally disposed drain formation on an outlet 41 depending from the pocket-like structure 33. The valve 40 is controlled by the handle 42 on the control panel 43, a rod 44 (see Figure 1) extending from the control handle 42 downwardly and laterally as at 45 to connect to the arm 46 on the valve 40.

Numerical 47 represents the switch knob for controlling the motor 10, while the heating element in the heating unit 34 is controlled by the switch knob 48. A pilot lamp 49 indicates when the heating unit is energized.

Numerical 50 denotes a perforated or side wall slotted basket, the bottom of which is formed with an upwardly extending socket 51 for receiving the upstanding pin 52 which rises from the plate 53. This plate 53 is soldered or otherwise secured to several of the ribs 28.

As can be clearly seen in Figures 4, 5 and 6, the impeller consists in construction of a plate 54 transversely tapered in opposite directions at opposite sides of the hub formation 55 at the intermediate portion thereof.

Outwardly leaning arcuate-shaped blades 56 rise from the plate 54, these blades extending toward the ends of the plate 54 from the hub 55 in inverted relation with respect to each other so as to describe substantially the letter S. The reduced edges of the plate 54 are on the open sides of the blades 56 thus permitting the plate 54 to pick up water from immediately above the heater 34 and allow the blades 56 to throw the picked up water laterally with considerable velocity.

While the foregoing specification sets forth the

invention in specific terms, it is to be understood that numerous changes in the shape, size and materials may be resorted to without departing from the spirit and scope of the invention as claimed hereinafter.

Having described the invention, what is claimed as new is:

A washing apparatus comprising a tub provided with a relatively small pocket in the bottom thereof, a fitting structure depending from the bottom of the pocket and consisting of a packing gland and a laterally disposed formation having a drain duct therethrough, a drive shaft disposed through the packing gland and upwardly through the pocket, an annular heating unit circumscribing the drive shaft and located in the pocket, an impeller at the upper end of the drive shaft just above the pocket, a spacing sleeve disposed through the annular heating unit and spaced therefrom and being interposed between the bottom of the pocket and said impeller, said heating unit being provided with a short depending formation adapted to rest on the bottom of the pocket to space the heating unit from the bottom of the pocket, said heating unit being of a size permitting a space to exist between the side portion thereof and the side of the pocket, a plug formation depending from the heating unit and adapted to extend through an opening in the bottom of the pocket to depend a distance below the bottom of the pocket and through an opening in the fitting, a nut on the plug formation adapted to be fed against the fitting to hold the fitting and pocket together, said plug formation and formation depending from the heating unit having a conductor duct therethrough, and a drain conduit extending from the said laterally disposed formation of the fitting.

WARREN C. PAULSON.
ALBERT KELLEY.
